TOILET DISK

Application filed October 2, 1925. Serial No. 59,979.

This invention relates to improvements in toilet disks or puffs as used almost universally by women and commonly called powder puffs.

An object of the invention is the construction of such puffs or disks and their manufacture at low cost, such disks at the same time being well made and possessing an appearance which is attractive and in harmony with the circumstances and accessories of their use.

The invention consists of the improvements in manufacture and construction of powder puffs described herein in connection with the drawings, from which description additional objects will appear.

Of the drawings:

Fig. 1 is a diagrammatic perspective serving as a general index of the manufacturing process and specifically illustrating an intermediate stage of one form of the preferred process, at which stage the first several rows of puffs or disks are completed in preparation for commencement of work on the rest of the width of the large sheets, said remaining work being in accord with the operations illustrated in Figs. 2 and 3;

Fig. 1A is a portion of one of the horizontal rows of disks shown in Fig. 1, in larger scale, to show the details of the results of the operations which have been completed in Figs. 2 and 3 on all the rows shown in Fig. 1;

Fig. 2 is a diagrammatic perspective similar to Fig. 1, but illustrating preliminary steps in the manufacture and including the manual work other than the needlework which is done in preparation for the needlework; this Fig. 2 showing the parts in positions for the work on the third row from the top in Fig. 2;

Fig. 2B is a portion of the single large sheet fabric in the middle of Fig. 2, this Fig. 2B illustrating a step in the operations of Fig. 2; this Fig. 2B illustrating the results of the operation shown in Fig. 2 in the third row from the top;

Fig. 3 is a diagrammatic perspective similar to Figs. 1 and 2, illustrating a later series of operations on four horizontal rows, on

which a first series of operations has been conducted in Fig. 2; this Fig. 3 showing the parts in positions for work on the second row from the top; and Fig. 3 illustrating the operations on three large sheets instead of only one as in Fig. 2;

Fig. 4 is a plan showing a modification or variant of the novel disk which results from a modification of the manufacturing;

Fig. 4A is a plan showing the modification of Fig. 4 in its uncompleted state of manufacturing;

Figs. 5-15 illustrate a modified form of the invention, the nature of the separate figures being described hereinafter, just preceding the description of the modified form.

Principal Figs. 1, 2, and 3 are of greatly reduced scale relative to the other figures.

The powder puffs made in accordance with the form of the invention shown in the drawings are employed principally with powder compact boxes. Heretofore it has been the practice to superimpose a plurality of disks upon each other, and, after placing a strip of ribbon on the upper layer, to secure the several parts together by stitching around the rim.

This proceeding, involving as it did the separate cutting of the disks and the manual assembly of a plurality of them to form the elements of a puff, was protracted and expensive. Also the manufacture must be such that the soft bottom fabric, which constitutes the part of the puff which is applied by the user to her face (and is of some soft pile fabric, such as lamb's wool), shall not have any securing stitches projecting from a part of its surface at or near the center where it is liable to abrade the user's skin.

Heretofore, so far as we are aware, no powder puff or method of manufacturing powder puffs has been devised which will permit the production at a practically low cost of a powder puff which is both strongly made and which is provided with attractive ornamentation.

In accordance with our present invention, such a puff and process are provided, wherein a desired ornamentation is produced which has no abrading effect on the user's

skin, and wherein the ornamentation itself may be made to serve as a physical means of securing together the parts of the puff, and specifically wherein such securing means consists of embroidery which greatly enhances the appearance of the article; and also wherein the embroidering, whether merely ornamental or mechanically functional, or both, is performed at greatly reduced cost.

As shown in Figs. 1A and 12, the compound fabric T, I, B, of great length and yard width (consisting preferably of three separate thicknesses of different fabrics to be described), is completed to contain a multiplicity of substantially or entirely completed powder puffs, and then the latter are cut out individually, being then ready or nearly ready for sale.

As shown in Fig. 1, the three fabrics which are assembled in multiple (Fig. 3), for the manufacturing operations, are in the form of fabric sheets as they come from the loom, a yard wide, more or less, and a number of yards long, a length of thirty to forty-five feet, for example, being cut off for treatment as in Figs. 1-3, etc. according to our invention. This length, however, may be doubled, i. e., to sixty to ninety feet long, under certain circumstances described hereinafter, for temporary or simultaneous operation.

Three fabric sheets usually are employed for the three layers of the disk or puff to be made, as shown in Fig. 1A at B, I and T. The bottom sheet B, the one which lies against the powder compact in the box, and which engages the skin of the user, is the actual puff and consists of some soft pile fabric, as of lamb's wool, eider-down or velour. The various useful and ornamental items of needlework shown in Fig. 1A should not extend thru to this soft surface of bottom sheet B, save for such stitches as 4 (Fig. 1A) located near the peripheral edge of the puff or disk.

The intermediate fabric I is a filling to stiffen and give body to the puff, and it may consist of buckram, crinoline, canvas, paper, or the like, as desired.

The top sheet T is the ornamental cover, consisting of satin, silk, leather, cotton fabric, or the like, as desired. It conceals the intermediate stiffener I and carries the ribbon handle A (Fig. 8).

Three large sheets of such materials are set up for treatment according to the invention in the manner shown in Fig. 3; that is, the three sheets are supported free in space, preferably vertically, as shown, their upper and lower selvage edges being pinned (at P) to the end edges of upper and lower canvas supports V, which, like window shades, have their other end edges secured to upper and lower rollers R, arranged to be rotated into positions adjusting the fabric sheets B, I and

T (superposed on one another) to any desired position relative to the multiple embroidering needles to be described. By means of supporting canvases V and rollers R, the long sheets for the manufacture of the puffs can be kept taut, in the various stages of the manufacture, so that the parts of the sheets can be held in sufficiently definite positions to permit registry of the successively-produced stages of needlework. In addition to the pinning at the selvage edges, the ends of the large sheets may be engaged by any suitable clutches (not shown) for the same purpose of maintaining the sheets in a sufficiently taut but not distorted condition.

As shown in Fig. 2, during the initial stage of fabrication the lower layer B and intermediate layer I are raised clear of the top layer and are temporarily held in this free or cleared position by temporary securing means such as pins P.

After the three sheets have been temporarily fastened in the positions shown in Fig. 2, and after rollers R have been turned to adjust the large sheet T to a condition of undistorted tautness, said satin top sheet T (Fig. 2) is ready to be operated upon by the permissible and highly advantageous multiplexing by means of any desired embroidering machine, of which the details form no part of our invention. In this position for the commencement of operations, the satin top sheet T is held smooth in a vertical plane, and sheets I and B are supported in positions which leave satin sheet T free, altho in readiness for I and B to be changed to the positions of I and B, shown in Fig. 3, for later stages of manufacturing. In this position of satin top sheet T in Fig. 2 the embroidery may be done manually, with the accompanying advantages of suitably supporting materials for hundreds of puffs in one situation, while holding the materials for each puff in positions which permit such manual embroidery. But the more important economic advantage is not only that, but more than that, i. e., that the method permits the manufacturer to avail himself of existing embroidery machinery by which the needlework itself, whether mechanically functional or merely ornamental, can be done at a very large saving in time and expense as compared with hand embroidery or other securing stitching. Furthermore, the invention is adapted for execution by any of the various well-known forms of embroidering machines, such, for example, as that which is controlled by a skilled artisan via a pantograph.

Rollers R may be mounted in frames F (Fig. 1) in proper relation to the embroidering machinery shown diagrammatically as including any suitable pantographic apparatus G and including a carrier C for multiple needles N, and also suitable shuttles on another carrier C (if used and not shown),

on opposite surfaces of the large sheets B, I and T.

With the parts in the position shown in Fig. 2, with satin or top sheet T extending alone downwardly with its lower selvage edge on or near lower roller R, and with intermediate and bottom fabric sheets I and B held out of the way of the shuttles on carrier C away from satin or top sheet T, the embroidering machine may be operated to embroider on satin sheet T a top row of duplicates of any arbitrary design, such as the hearts 1 of Fig. 1A, the same extending in a long horizontal row, as shown, in part, in Fig. 2, from one end to the other of the very long sheet T (Fig. 1).

Such initial embroidering of design 1 fixes and determines the parts of the large sheets T, I and B which are to constitute the powder puffs themselves, prior to the dieing operation. This operation, like all the other embroidering operations herein, when conducted on an embroidering machine of the pantograph type, is effected by the human or automatic operator of the pantograph, who or which moves the pantograph control in accordance with a master or index model, and in accordance with a sample of the desired design at which he is looking. Any such machine may be of the shuttle type or of the type termed "hand" embroidery machines because their product in quality resembles hand-made work.

Upon the completion of the top row of designs 1 (Fig. 2), which occupies but a few moments when effected in an embroidering machine, unskilled labor is employed to temporarily secure a narrow ribbon A, as by pins Q (Fig. 2), to satin or top sheet T just below said top row of designs 1, and likewise extending horizontally from left to right (Figs. 2 and 1) for the entire length of sheet T, and within the areas of the portions of the sheets later to be died out as puff-disks. Such pinning preferably is on a portion of sheet T which is left after the dieing operation, as shown at Q in Fig. 1A. This pinning, of course, is temporary and is for the purpose of holding the ribbon in proper position pending the next manufacturing step, the result of which is shown in Fig. 1A, i. e., the permanent securing of ribbon A to sheet T by means of embroidered ring-stitches 2 appearing as circles with radial threads. Preferably and actually, these radial threads are closely adjacent to one another, this being attempted to be illustrated in the drawings by two adjacent radial lines showing sides of each thread and each line serving to represent the adjacent sides of adjacent threads. This step permanently secures ribbon A to satin or top fabric T by stitches which incidentally and usefully are ornamental by being in the form of embroidered ring-strokes.

The entire top row (Fig. 2) of these ribbon-

securing embroidered circles 2 is embroidered simultaneously when done, as preferred, by the multiplex needles N; and, likewise, the second row in Fig. 2, as shown.

While fabric sheets T, I and B are in the positions shown in Fig. 2, i. e., with T free of I and B, another embroidering operation usefully may be effected on satin or top sheet T, i. e., prior to the assembling of the three sheets shown in Fig. 3. This operation consists in embroidering the inner circle 3 (Fig. 1A) at the inner rim of circle 2, in order further to secure ribbon A to sheet T and also to impart a finished appearance to the inner rim of embroidered circle 2. Circle 3 is exactly like circle 2, save that it is narrower radially; circles 3 being made in a given horizontal row just after circles 2 have been made in that row, i. e., without turning rollers R to move sheet T to a different position. In some cases narrower inner circle 3 may be relied on alone as the means for securing ribbon A to satin sheet T, prior to the operations of Fig. 3.

When the top row is completed, on sheet T alone in the positions shown in Fig. 2, and when narrower inner circles 3 are included in these operations, the puffs in such row are in the state including the initiating ornamental embroidery 1, the ribbon-handle A, and the ribbon-securing circles 2 and 3 of broad and narrow widths, respectively, but not the embroidery ring-stitch circles 4, Fig. 1A which are to be made in the step of the process illustrated in Fig. 3 for the purpose of permanently securing together all three sheets T, I and B at each of the multiplicity of the puffs in the four rows which have been partially completed in the step of Fig. 2.

During all this time (and considering only the completion of the operations under the circumstances of Fig. 2) rollers R and supporting curtains V have been holding sheet T in position, so that the top row of Fig. 2 can be worked on by the needles N and the shuttles carried by frame C in Fig. 1. Now that the top row in Fig. 2 has been completed (yet considering satin or top sheet T alone and not sheets I and B), the rollers R are turned so as to move satin or top sheet T upwardly, to bring another horizontal portion of the length of the latter (Fig. 2) within the field of influence of multiple needles N; and rollers R also are adjusted so as to hold sheet T with the desired degree of tautness in this, its new position. Thereupon, in the second row from the top, as above described with respect to the first row, initial designs 1 are embroidered, a second ribbon A is pinned temporarily in position, and ribbon-securing and ornamental embroidery design 2 is made, as shown in the two top rows of Fig. 2 (and also circles 3 of Fig. 1A if desired).

After the second row has been embroidered

in the manner described the sheet may again be moved vertically upwardly and the operation repeated for the third and fourth rows.

The mechanical functions of the operations illustrated by Fig. 3 are the securing together of all three sheets T, I and B at each of the multiplicity of the puffs in the four rows which have been completed in Fig. 2. This matter of the completion of a limited number of rows in Fig. 2, extending only part-way of the width of sheet A, prior to the operations of Fig. 3, is involved in the matter of registry to be explained later.

Up to the completion in Fig. 2 of the product nothing has been done with the large puff sheets I and B, save to keep them out of the way of the embroidering while sheet T was having the four ribbons secured to it by the ornamental embroidery of the four rows of Fig. 2; and in Fig. 2 none of the embroidering has extended thru sheets I and B, but only thru satin or top sheet T.

Next, in Fig. 3, the lower selvage edges of sheets I and B are let down, so that both these sheets lie adjacent to satin sheet T and back of it; the bottom selvage edges of sheets I and B being pinned, at P (bottom Fig. 3), to the upper edge of lower supporting curtain V, i. e., where the lower edge of satin of top sheet T is pinned; that is, the lower selvage edges of all three puff sheets are there pinned together and the rollers R are adjusted so that all three sheets lie adjacent one another in a condition of the desired tautness between their upper and lower edges thruout the entire length of their many yards, more or less. All this pinning and changing of locations is performed in the intervals of machine embroidering effected by the skilled artisan at the pantograph or by automatically controlled embroidery machines.

With the three puff sheets pinned together as shown in Fig. 3, rollers R are turned back in a direction opposite to their turning in progressively completing the four rows of Fig. 2, so that now the top row is brought opposite multiple needles N on carrier C. After the pinning operation in Fig. 3, and prior to any embroidering in the positions of Fig. 3, the work in all the four rows in Fig. 3 is in the condition shown in Fig. 2A.

In the triple puff sheet arrangement of Fig. 3, with all four rows with finished puffs like the top row of Fig. 2 and with rollers R adjusted so that the top row is alongside the horizontal row of multiple needles N, the pantograph operator causes the production of embroidery ring-stitch circles 4 at the outer rim of ribbon-securing embroidery circle 2. Circle 4 preferably is of narrow width, similar to circle 3, which secured ribbon A to satin sheet T as described above; and this circle 4, like circle 3, provides an attractive finish to circle 2, i. e., at the outer rim

of the latter; but the physical function of circles 4 is not only to secure ribbon A by additional means to sheet I, but principally to secure together all three fabric sheets T, I and B and thereby produce puffs of the consequent compound fabric, which puffs are completed save for the cutting out of the puffs from the wide and very long compound fabric sheet. Said outer or rim circle 4 marks the extreme outer edge of each of the multiple puffs, and it is the only portion of the needlework which extends thru the three sheets of the compound fabric, so that this embroidered circle 4, which extends thru the soft bottom pile fabric B, exists only at the outermost edge of each puff-disk thereof, in a location least likely to abrade the person's skin. In Fig. 3 the top row is shown as having rim embroidery circle 4 made on all the puffs of the row, as shown enlarged in Fig. 1A. The lower three rows of Fig. 3 yet are in the same stage as the top row of Fig. 2; and multiple needles N are shown in Fig. 3 in position to make outer rim circles 4 around the puffs in the second long horizontal row. Rim circles 4 are made on the remaining two rows successively by alternate operation of rollers R and of the pantograph G (Fig. 1).

When thus the puffs in all four rows of Fig. 3 are completed, the bottom pinning of backing sheets I and B to satin sheet T and lower supporting curtain V is removed, and their lower edges again are pinned up at elevated positions (Fig. 1) to upper supporting curtain V. But this row of pins P in Fig. 1 is not so high as that of Fig. 2, because now in Fig. 1 the three fabrics T, I and B are secured together at the top four rows as the result of the operation in Fig. 3 on such four rows, by means of the outer rim embroidery 4. This repinning up in Fig. 1 is high enough, however, to free satin or top sheet T of its backing sheets I and B at that portion of sheet T which lies directly below the four top rows, where now are to be made a second set of four more lower rows, in accordance with the operations already described in connection with Fig. 2, and in the positions of large sheets shown in Fig. 1.

The practical reason why, in the operation of Fig. 2, sets of only about four rows, more or less, of puffs like Fig. 2A are made in a given relation of the large sheets and under the circumstances of Fig. 2, and why, in the operation of Fig. 3, sets of only four rows, more or less, are made in a different given relation of the large sheets, is found in the matter of registry. Two principal stages of operations are involved, i. e., those of Figs. 2 and 3; i. e., first, in Fig. 2, the desired embroidering, such as 1 and 2, etc., useful physically and/or esthetically, is effected on sheet 2 alone, and second in Fig. 3 the desired embroidering, such as 4, similarly useful, is ef-

fected on all three sheets T, I and B, or at least on two sheets, including sheet T, in case a single sheet or a double compound sheet be used in place of two separate sheets I and B. While twelve rows of puffs usually are made in the triple compound sheet extending across the width of the sheet (i. e., three sets of four rows each), yet in sheets of one yard width and for puffs of ordinary small diameter, there may be four or five or more sets of rows, each containing four rows, more or less; and while the large puff sheets are held as taut as may be, without distortion, between upper and lower supporting curtains V, yet these extensive sheets (considering sheet T alone or even one or two backing sheets pinned with sheet T at or near their edges) are not at all rigid between the upper and lower lines of pinning or free from liability to movement of parts of a given sheet relative to one another, or of parts of one sheet relative to adjacent parts of an adjacent sheet, during the various manufacturing operations prior to the securing of the sheets together by the outer rim embroidery circles 4 in the operations of Fig. 3. Also, if the entire width of satin sheet T were treated continuously, according to the operations of Fig. 2, then it would be very difficult, if not practically impossible (on account of the stretching of the fabric at different stages of its operation and consequent relative movements of its parts into different positions), to conduct the operations of Fig. 3 so that embroidery circles would register as desired with the embroidering simply because the latter might not be uniformly distributed over sheet T. But we have found that it is not necessary to limit the ribbon securing operations of Fig. 2 to a single row of embroiderings, prior to conducting the sheet securing operations of Fig. 3, for if satin or top sheet T be held as taut as is practicable, without distortion, by means of the top and bottom rows of pins P and by the end clutches (not shown) at the ends of sheet T, then at least four rows and even more of the work of Fig. 2 may be effected prior to the securing together of the three sheets as in Fig. 3; that is, without undesirable lack of registry between embroidery circles and the prior embroidery. The completion in Fig. 3 of the top four rows (more or less) by the embroidery-sewing together of the plural sheets at multiple circles 4 throughout the length of the compound fabric has the effect of causing the four rows of circles 4 of Fig. 1 to serve (as a means of holding the large sheets sufficiently taut) like the row of pins P in Fig. 2 at the top selvage edge of satin or top sheet T in the sense that said sheet T (Fig. 1), as to its portion of several inches below the fourth row of circles 4, is held taut by means of said rows of circles 4 extending thru the three large sheets and thereby causes that

portion of the sheets to be a comparatively rigid compound structure. That is, by the circles 4 of Fig. 1, the long horizontal portion of sheet T, in the region of a few inches below the lowest or fourth puff-row, is held in sufficiently taut position to permit the production of a second set of four rows (more or less) of puffs below the first sets of rows, by the operations of Fig. 2, resulting in four more rows like the product of Fig. 2A. During the production of this second set of rows by the operations of Fig. 2, the three large sheets are in the relations shown in Fig. 1, which shows the beginning of the second set of Fig. 2 four-row operations; sheets I and B now being pinned up again, or rather the parts of sheets I and B not yet secured by embroidery 4 to satin sheet T being pinned up again, in the positions shown in Fig. 1, so as not to interfere with this second set of Fig. 2 operations, producing the second or lower set of a plurality of rows of puffs. Here (Fig. 1) sheet T yet has its upper edge secured by pinning to upper supporting curtain V, and now is secured by embroidery stitching 4 to the upper portions of sheets I and B, so that not only is the upper part of sheet T held in an elevated position away from its lower part about to be subjected to the second set of four-row operations of Fig. 2, but, in effect, as to the tautness of the lower portions of sheet T not yet embroidered to sheets I and B, said sheet T is suspended from the lowest of the four rows of embroidered circles 4 which secure the three sheets together.

The second set of four rows of puffs, is now made on sheet T, and made successively, as above described with reference to the making of the first set of four rows in Fig. 2. Next, said second set of four rows of Fig. 2 is subjected to a second set of operations above described with reference to Fig. 3, rollers R being manipulated, and backing sheets I and B being changed, as before, from the positions of Fig. 2 to those of Fig. 3.

The above cycle of operations is repeated until the entire width of the compound fabric is covered with puffs including the results of the respective operations of Figs. 2 and 3.

When the lowest row of puffs is being produced according to the operations of Fig. 2, (next the lower horizontal edge of sheet T), the lower edges of sheets I and B will be held up by pinning to the upper completed portions of the embroidered compound-puff fabric itself, instead of to the upper supporting curtain V; and during the operations of Figs. 2 and 3 on the lowest portions of the width of the compound fabric, the upper completed portions thereof may be wound, together with upper curtain V, upon upper roller R.

It will be understood that the invention is

practical and useful, notwithstanding the fact that the completion of the compound fabric M may represent a full day's work of a skilled artisan and several unskilled women operatives, because, while a large proportion of the time and labor is used in the manipulation of sheets T, I and B, yet all that permits of the use of the embroidery machine, which saves in time and labor as compared with the manual embroidering or stitching together of the thousands of puffs included in the single compound fabric.

The method of registry again is involved in the cutting out of the finished puffs from the compound fabric M. Since the outer edge of the outer or rim embroidery securing circles 4 of Fig. 1A is located at what is desired to be the outer edge of the finished puff itself, without any projection, beyond said embroidering, of any portion of sheets T, I and B, (which of course would be unsightly) it is important that the puffs be cut out of the compound fabric M with extreme accuracy, for the purpose of avoiding any cutting of said stitches themselves in an attempt to prevent any bad-looking fabric projecting beyond said stitches. The accuracy required for this is of a greater degree than that required in the successive operations of embroidering, first on satin or top sheet T and then on all three sheets together; and while said successive embroiderings all may be done on the same set-up (save for the changes as between Figs. 2 and 3), yet we have found that the only practical way to cut out the puffs from the compound fabric M is by the manual operation of an ordinary collet. This method effects the desired result above stated, even altho the puffs in compound sheet M (or rather embroidered rim circles 2 and 4 thereof) be not equally spaced from or exactly concentric with one another. In the operations of Figs. 2 and 3, it is practicable to produce embroidery circles 2, 3 and 4 with sufficient concentricity to avoid an unattractive appearance, but even so the outer circle 4 of a given puff may be spaced differently from circle 4 of any two or more adjacent puffs. But the operation of the collet punch is with respect to the puffs individually, and gives free scope to the attentive eye and responsive hand of the skilled operative in placing the collet accurately around the outer circles 4 of the various individual puffs, the cutting edge of the collet being only of very slightly larger diameter than circles 4, so as not to leave only portion of sheets T, I or B projecting beyond circles 4, altho not cutting any of the threads 4. Thereby the compound sheet M is cut along a multiplicity of lines surrounding but closely adjacent the multiplicity of circles 4 so as to cut out the completely assembled toilet disks comprising a plurality of disk sheets already secured together.

65 Our invention permits as much embroidery

ornamentation at both sides of ribbon A, or generally on satin or top sheet T alone, as may be desired, with very little difference in cost when the embroidery is effected by the machine, as is, of course, preferred to manual embroidery within the invention. And since embroidery designs 1 and 1A in Figs. 4 and 4A each is arbitrary in an esthetic sense, they may be alike, or, in fact, either of them may be of any desired design believed to enhance the beauty of the product. And ribbon A need not extend diametrically across the puff, as in Fig. 4, for it may extend as the chord of a smaller arc of the circular disk, leaving more space on one side of ribbon A for a larger design 1 or for a plurality of designs 1, with or without any design or designs 1A on sheet T on the other side of ribbon A; and any design on sheet T alone may include lettering or a word or words on either side of ribbon A, and on any portion of the top surface of sheet T. Or in Fig. 4, one of the designs 1 and 1A may be omitted and replaced by handle A, whether that consists of the overlock stitching to be described or of a ribbon; or the center design of Fig. 9 may be wholly omitted and, if desired, the free end of handle A2 may be extended further toward the center of satin disk T. All such variants are quite arbitrary within the operations of Fig. 2 on the top of satin or top sheet T alone, i. e., not extending thru the soft or bottom disk B to abrade the user's skin; and the class including any and all such variants is permitted to be economically produced by virtue of the invention, which, notwithstanding the embroidered securing together of the three sheets T, I and B, permits simultaneous multiple production of both the ornamental designs on top of sheet T alone and also the securing design for the three sheets together, all in a common set-up of the large sheets in free positions in space which permit the embroidering to be effected.

In all embodiments of the invention which include any form of handle on the top of satin sheet T, which handle is separate from the fabric sheets and the stitching, the operations include the step of some form of embroidering which extends at least thru both satin or top-disk fabric T and a part of the ribbon itself so as to permanently secure the two together.

In threading up the shuttles and needles for any embroidering which extends thru the entire compound puff-fabric, the shuttle-threads (i. e., the threads supplied to the back of bottom sheet B, Fig. 3) are of the same color as sheet B itself, which commonly is white; for these threads show on bottom sheet B, and it is desirable not to have them contrast with the rest of the bottom. On the other hand, the needle-threads (i. e., the threads supplied to the front of sheet T, Figs. 2 and 3) are of any desired color, usually

contrasting with the color of usually colored sheet T, to contribute to the ornamental effect of the embroidering.

The operations of the principal Figs. 1, 2, 5 and 3 may be varied, individually and relatively, for the purpose of producing variants of the puff shown in Fig. 1A for example, as follows.

In Fig. 4 is shown a rim construction 24, 16 which is different from and which replaces that at 2 and/or 4 of the puff in Fig. 1A. In Fig. 1A the embroidery circles 2 and 3 were described as being made in the Fig. 2 relations of the large sheets T, I and B, both 15 circles 2 and 3 serving to secure ribbon A permanently to satin sheet T alone; and also in said Fig. 1A, the outer embroidered rim circle 4, made in the Fig. 3 portion of the manufacture, served to secure together the 20 three sheets T, I and B.

In Fig. 4, however, after satin or top sheet T has been acted on in the Fig. 2 stage, to produce arbitrary initiating design 1, to have ribbon A temporarily secured to sheet T, as 25 by pins P, and with or without second embroidery designs 1A, then sheets I and B are brought down adjacent top or satin sheet T, as shown in Fig. 3, prior to the embroidering of ribbon-securing circle 3. Said embroidered circle 3 is yet retained in Fig. 4, however; but, being made during the operations of Fig. 3, (i. e., so as to extend thru all three sheets T, I and B), it not only serves to secure ribbon A to top satin sheet T, but also now 30 secures together all three sheets T, I and B. In this case, the sheet-securing embroidered circle 4 of Fig. 1A is not needed, may be omitted, and is omitted in Fig. 4, being replaced, in function, by circle 3. At this stage, 35 i. e., with any desired ornamental embroidery on sheet T alone, with embroidered circle 3 securing ribbon A to sheet T, and securing together all three sheets T, I and B; but as yet without any rim-securing outside of embroidery circle 3, the puff is cut out of the compound fabric M by some suitable method whereby the skill of the operative is relied on to execute the cutting out at circles further removed from circles 3 than the necessary but 45 slight spacing of the cutting lines from circles 4 of Fig. 1A, but yet at circles which substantially define the rim of the completed puff-disk. That is, the puff lacks the embroidered circles 2 and 4 of Fig. 1A, altho 50 retaining an embroidered circle 3 substantially remote from the center of the puff-disk and substantially defining its periphery. But embroidered circle 3, in its new capacity, is the means of securing together all three sheets 55 T, I and B; and, being a smaller circle than embroidered circle 4 of Fig. 1A, it is located slightly more remote from the edge of the bottom of the puff-disk than was embroidered circle 4. At this stage of the production of 60 the puff of Fig. 4, it is subjected to treatment

in an ordinary sewing machine having an overlock stitch attachment, wherein, with the needle operated by the machine, the skilled operator moves the rim of the puff-disk around under the needle to produce the overlock stitching 24, shown in Fig. 4 as surrounding the entire edge of the puff-disk. This overlock stitching 24 extends radially from the edge of the disk substantially as far as embroidered circle 3 (Fig. 4), so that, on 70 the satin-faced top of the puff, embroidered circle 3 constitutes an attractive finish for the inner edge of the overlock stitching 24, in addition to the functions of embroidered circle 3 in securing ribbon A to satin sheet T, and particularly in securing together sheets T, I and B, so that, after dieing out from the large sheets, the puff-sheets are fully assembled for 75 great practical convenience during the operation of producing overlock stitching 24. Such 80 bottom rim finish effect 24 of Fig. 4 can be obtained, in less ornamental degree, by producing wide embroidered circle 2 during the operations of Fig. 3, (instead of Fig. 2 as above described), i. e., so that such circle 3 extends thru all three sheets T, I and B and shows on 85 the bottom of sheet B somewhat like overlock 90 24 at the turned-up portion of Fig. 4; but in such case the colored embroidery needle threads showing at bottom B are liable to be 95 uneven and give an appearance less attractive than overlock 24 of Fig. 4. Furthermore, the 100 embroidery shuttle threads (applied in back of bottom B, Fig. 3) extend forwardly or upwardly thru to the surface of satin or top sheet T, so that if such embroidery shuttle threads are white, to match the usually white bottom sheet B, and if, as is preferred, the 105 satin or sheet T itself be colored and the embroidery needle threads be colored, then such 110 contrasting white shuttle threads, showing on the exposed surface of satin or top sheet T, produce an undesirable appearance. For this reason, it is worth while to modify the manufacture, involving the production of 115 overlock 24, as above described, altho this involves a slight increase in cost per puff, and all for the purpose of obtaining a better appearing puff; altho in both cases, i. e., of the wide embroidery circle 4 extending entirely 120 thru the puff, and of the overlock 24 of Fig. 4, the mechanical effects are about the same.

The invention may be employed usefully in connection with the different type of powder puff shown in Figs. 5-7 which is a wholly 125 flexible soft general utility puff used with actual powder, as distinguished from the comparatively stiff pad of Figs. 1A, 2B, 4-4A.

Figs. 5, 6 and 7 show the construction of this general utility type of puff on which the 130 improvements have been made as illustrated in Figs. 8-15; Fig. 5 being an edge elevation, Fig. 6 a vertical section thereof, and Fig. 7 a plan.

This form of puff, wholly soft and flexible,

and capable of general use, generally is used at the dressing table but also frequently in a flexible container carried in the pocket book, the powder content being renewed daily at 5 the dressing table. All three of its disk-sheets T, I and B (Fig. 6 section) are soft and flexible, its intermediate member I is not a stiffener as in the pads of Figs. 1A, 2B, 4-4A, the entire puff is much thicker (Figs 5-7), the 10 intermediate member I being a filling or puffing member; and usually the entire puff is of larger diameter and therefore not so conveniently carried in a rigid box. The outer surfaces of both the outer members T (top) 15 and B (bottom) are soft as of pile fabric (shown in stippling Figs. 5 and 7) both consisting of velour-like material and there is no satin or other similar colored ornamental top-disk and no white bottom at B as in Figs. 1A, 20 2B, 4 and 4A. The outer pile surfaces T and B, in which lie the pile-threads, usually are of the same material, color and appearance, being some attractive color such for example as pink, and both these outer disks are useful 25 powdering surfaces, altho commonly there is a ribbon handle A (Figs. 5-7) extending over the top, the puff being of sufficiently large diameter to receive a ribbon permitting the insertion of three fingers in applying the 30 puff to the face, altho sometimes the ribbon handle is in the form of a short tab, but there need not be any handle at all. The intermediate or filling member I is of any desired low priced soft material, such as cotton batting.

But the principal feature of this type of puff, in connection with the present invention, is that, altho the three disk-sheets are secured together by rim-stitching shown at 5, in the 40 section Fig. 6 (including the ribbon handle A when present) yet such stitches are not visible. Heretofore such stitching has been done on an ordinary sewing machine while the three disks were inside out, so to speak, 45 such stitching not extending entirely around the rim; and the partially-secured-together disks then were turned right side out and the securing rim-sewing was completed around the circumference by skilled needleworkers 50 producing substantially invisible stitches so as to mask the rim-joint between the edges of the outer soft disks T and B, Fig. 5. Thus the attractive appearance of this form of puff has been due to the lack of plainly visible 55 rim-stitching. But the above described prior rim-stitching, for securing the three disks together, has been costly, and no practicable means has been devised for producing embroidery on either the top or bottom faces of 60 this soft general utility puff. The employment of the present invention in the production of the improved form of this type of puff is illustrated in Figs. 8-11. This involves a substantial modification of the invention as 65 embodied in Figs. 1-4A, altho it involves

nearly as great advantages in reducing labor-cost while permitting improved ornamentation, as does the modification of Figs. 1-4A.

Fig. 8 is a perspective of a large sheet T similar in shape to that of Fig. 2, and illustrating a condition of the product in process 70 similar to that shown in Fig. 2;

Fig. 9 is a perspective showing the reverse surface of sheet T of Fig. 8;

Fig. 10 is a view like Fig. 8 but showing 75 large sheets I and B in combination with large sheet T in process, analogous to sheets I and B of Fig. 2;

Fig. 11 is a diagram illustrating the relations of the three sheets after sheets T, I and 80 B of Fig. 10 have been dropped down over the opposite surfaces of the first sheet T;

Fig. 12 is a fragmentary view of the three sheets of Fig. 11, illustrating the embroidered 85 circle 4 resulting from an operation involved in the operations of Figs. 1-3 upon the three sheets in their relations illustrated in Fig. 11;

Fig. 13 is a perspective illustrating the product of a dieing-out operation upon the 90 three sheets secured together in the operation of Fig. 12;

Fig. 14 is an edge view of the product shown in Fig. 13 after the latter has been turned inside out, the three sheets being secured together in Fig. 14 by the embroidery circle 95 4 of Fig. 12 now substantially invisible, and the permissible ornamental embroidery 1 of Fig. 10 now appearing on the outside of the puff as the result of turning inside out;

Fig. 15 is a view like Fig. 7, of the puff 100 completed by the completion of circular securing embroidery 4 of Fig. 12 by hand-sewing to close up the opening which permitted turning inside out; Fig. 15 apparently differing from Fig. 7 only in the provision of 105 the ornamental embroidery 1, altho actually also the rim-stitching 4 of Fig. 12 which secures the three disks in the assembly of Fig. 15 also is formed by embroidering in multiple on the large sheets in the relations shown in 110 Figs. 11 and 12 and to be described in connection with the method of production of such ornamental embroidery as 1.

In Fig. 8, sheet T is set up like sheet T of 115 Figs. 1 and 2; sheet T here like sheet T there, being the sheet out of which are made the disks for one of the outside members of the puff. Only a small part of the horizontal length of this sheet T is shown in Fig. 8, and it is there also broken away at the top, as also in Fig. 9; but this entire set-up is 120 similar to that described in connection with Fig. 1, where the vertical extent of the sheet is a yard more or less and the horizontal extent is preferably many yards long. In Fig. 8 the pile surface PS of sheet T is presented to the eye, this being the surface which is to constitute the exterior soft surface of the eventual puffs. On pile surface PS is applied a ribbon A, by pins Q as in Fig. 2, 125

in cases where a ribbon handle is desired for the final puffs. Then, as described in connection with Fig. 2, the desired ornamental embroidery, as at 1, 1, is produced in multiple along horizontal rows on sheet T. These embroideries preferably are made simultaneously throughout the entire horizontal row, as heretofore described and at spaced intervals in the row in accordance with the desired 5 diameters of the puffs eventually to be produced. Fig. 9 shows the reverse or fabric surface FS of pile sheet T, this being the surface which is to lie in the interior of the completed puff, against intermediate or filling sheet I, Fig. 6.

In Fig. 10 is shown how sheets I and B are combined with sheet T in the general set-up of Fig. 1 for this soft type of puff. While both I and B are supported as by pinning at their top edges, to the lower portion of upper canvas V, so as to expose their outer surfaces (as in the case of sheet T, Figs. 8-9), and while I and B are bodily supported out of the way of the ornamental embroidering operations on sheet T in Figs. 8-9, as by pinning the lower edges of I and B in a higher position, as in Figs. 10 and 2, yet now in Fig. 10 sheets I and B are disposed upon opposite sides of sheet T instead of being both on the same side thereof as in Fig. 2. The intermediate filling sheet I is on the back or fabric side FS of ornamenteally embroidered sheet T. Sheet B is on the opposite or pile surface side PS of sheet T. After the completion of the ornamental embroidering such as 1, 1, etc. on sheet T in Figs. 8-10 the lower edges of sheets I and B are unpinned (at the upper part of Fig. 10) and said sheets are dropped down into the 20 positions illustrated in the diagram, Fig. 11, (being suspended from the lower edge of upper canvas V) in which figure the sheets are shown as separated from one another only for the purpose of showing the relations of 25 their surfaces. Thus, in Fig. 11, the pile surfaces PS of sheets T and B face one another, as is also indicated in Fig. 10; the fabric surface FS of sheet B facing away from the pile surface PS of sheet T. The pile surfaces PS of sheets T and B are to constitute the outside surfaces of the eventual puffs; and sheet I is to constitute the filling member between them in the puff, altho in Figs. 10-11 sheet I is shown on one side of sheet T and sheet B on the other. This arrangement, for 30 the operations of securing the three sheets together by multiple embroiderings, is for the purpose of causing the sheets to lie in the proper described relation to one another after, upon permanent assembly by the embroidering operation into puff units, they are turned inside out.

With the three sheets in the relations illustrated in Fig. 11, and in the set-up of Fig. 35 10 and under the condition where the three

sheets are located face to face and close to one another, the lower edges of sheets I and B are pinned to the upper edge of lower canvas V, Fig. 10, just as are sheets I and B in Fig. 3. Before the dropping down of 70 sheets I and B to the relations of Figs. 11-12, the operations correspond to those of Fig. 2 above described, but in the present case those operations consist only in producing the ornamental embroiderings 1, no extra ribbon-securing circles 3 (Fig. 2) being here necessary as will be seen.

In Fig. 12, (showing only a fragment of the three large face-to-face assembly sheets for one of the multiplicity of puffs) the three large sheets are in the relations shown in Fig. 11, all pendant from upper canvas V and all having their lower edges pinned to lower canvas V of Fig. 10. The operation of Fig. 3 thereupon is executed to produce substantially circular embroiderings 4 of Fig. 12 in multiple, and these circles 4 not only secure the three sheets together at the puff-rims, but also secure ribbon A to the three sheets. Circles 4 are not for ornamentation, 80 being eventually concealed in the assembly. Hence, in Fig. 12, there is no necessity for additionally producing circles 3 of Fig. 2 for the purpose of securing ribbon A to sheet T preliminary to the securing of the three sheets together by circles 4 of Fig. 3, because here the ribbon A is secured by embroidering circles 4. The respective multiple circles 4 of Fig. 12 are spaced along the horizontal rows, Fig. 10, so as respectively to extend 85 around the multiplicity of ornamental embroiderings 1, Fig. 10 and to extend over and through ribbon A (between pins) so as to secure the latter to the large sheets. Circle 4 of Fig. 12 also is made to be somewhat less than a complete circle as shown, but preferably of a sufficient arc so that both its ends extend over ribbon A. Preferably, as before in Fig. 3, all the circles 4 in a single 90 horizontal row are produced simultaneously. Also, as described in connection with Figs. 1-3, the sheets are moved vertically after the completion of each row of embroiderings and before the commencement of the next row of embroiderings; this applying 95 both to the ornamental embroidering 1 of Fig. 10 and to the securing embroidery 4 of Fig. 12. Upon completion of all the circular embroiderings 4 of Fig. 12 on the plural sheets, throughout the length and breadth thereof (Fig. 1), the pins P of Fig. 10 are removed, which have served to secure the sheets to upper and lower canvases V; whereupon the individual puffs are died out to produce 100 toilet disks like those of Fig. 13, the dieing out being preferably in accordance with the above description of the operation of dieing out the puffs from the sheets of Fig. 3, all the circular cuts being made just outside of 105 circles 4 without injury to the embroidery 110 115 120 125 130

threads of such circles, and between pins Q, Fig. 10 so that the pins are left with the waste portion of compound fabric T, I, B and no pins or pin-holes exist in the completed puffs, as shown in Fig. 15. In the case of this general utility puff, it is not so important as in the case of the pad of Figs. 4-4A to cut the fabric so close to the rim-embroideries as to prevent unsightly projection of fabric beyond the rim, this being because this puff is to be turned inside out; and hence it is more practicable to cut out a large number of puffs simultaneously from the large compound sheet, without danger of injuring the securing embroidery stitches, for the cutting dies may have a diameter substantially larger than that of securing circles 4. In Fig. 13 showing a died-out puff, the relations of the surfaces of the three sewed-together puff disks to one another are the same as those of the large sheets in Figs. 10-12. The lack of completion of embroidery circle 4 in Fig. 12 leaves in Fig. 13 an opening O which permits insertion of an operator's thumbs, while the fingers of both hands press on the outer surfaces of disks I and B in Fig. 13, thereby permitting the structure to be turned inside out so that the mutually facing inside pile surfaces PS of sheets T and B of Fig. 11 leave one another and become the outer faces of the puff of Fig. 14. In Fig. 14 now appears the ribbon handle A on the outside of the puff as well as the ornamental embroidery 1, disk I in Fig. 13, lying, in Fig. 14, between the outer disks T and B and adjacent to their fabric surfaces FS. (Now pins Q of Fig. 10 may be removed.) In this operation of turning inside out, the embroidery sheet-securing circle 4 of Fig. 13 disappears inside the puff, and the joint between outer disks T and B of Fig. 14 is only slightly visible as indicated by the dot and dash line of Fig. 14. In Fig. 14 however, the hole O yet is open, showing a portion of intermediate or filling member I; and as the final step in the manufacture, hole O is closed by a skilled needleworker whose stitches are so carefully made that they cause no more objectionable appearance than the dot and dash line of Fig. 14. The final product is shown in Fig. 15 as one of the multiplicity of puffs made from the large compound sheet T, I, B and each puff comprising invisible embroidered securing circles 4 (Figs. 12-13) securing together all three disks and the ribbon handle, and comprising also any desired ornamental embroidery, as 1, on the outer top face of the puff as the result of processing in multiple in the same set-up of Figs. 10-12 wherein the securing circles 4 are produced in multiple. Inasmuch as in the completed puff of Fig. 14, the securing circles 4 lie inside the puff and out of sight, the only apparent difference between this puff and the prior art shown in Fig. 7 is the ornamental embroid-

ery 1, altho actually our invention has permitted very low cost of production of both embroiderings 1 and 4 in the set-up of Fig. 10. While as a practical matter it is preferred not to provide ornamental embroidery on the reverse face of the puff of Fig. 14 yet in view of the above description it is clear that that may be done if desired, by producing any desired ornamental embroidery on pile surface PS of sheet B, Fig. 10, by reversing the surface of sheet B in Fig. 10 to bring such pile adjacent needles N, pinning up sheets I and T out of the way of sheet B, and thereupon multiplexing the desired ornamental embroidery designs, such as 1, upon the pile surface PS of sheet B.

Various advantages of the invention have been pointed out in connection with the above description of the drawings.

The above-described improvements in manufacturing powder puffs, which include what we believe to be the best forms, will suggest to persons skilled in the art various useful modifications of the invention of more or less utility and value. For example, the operation of cutting out the puffs with a die (altho this preferably is not effected until at least after the embroidery operations of Fig. 3, by which all three sheets T, I and B are secured together) may be executed upon satin sheet T alone as soon as the entire sheet T is filled with the embroidering which is effected by one or more of the operations of Fig. 2; and then, disks of like diameters having been cut out of sheets of material like backing sheets I and B, (independent of the cutting up of sheet T), such latter disks may be rim-sewn by any desired means to the multiple-embroidered and separately died-out satin puff disks T. And other modifications will occur to skilled persons as the result of our disclosures above. But clearly, the most advantageous form of our invention, as to lowest manufacturing cost, is that which takes advantage to the fullest of the completion of the puffs in multiple on large sheets freely suspended at their edges to expose their opposite surfaces, so as to permit embroidering access thereto, including not only such substantial completion in respect to one or more or all of the operations of Fig. 2 on satin sheet T alone, but also such substantial completion in respect of one or more or all of the operations of Fig. 3 on the plurality of sheets adjacent one another, and all prior to any dieing operation. (Compare Figs. 8-13.) However, the economy permitted by the invention is so great, when considered only in respect of the purely ornamental embroidery (and the ribbon embroidery) of Fig. 2 and of the multiple-disk-securing embroidering of the operations of Fig. 3, that it is yet economical, (while omitting most or all of the embroidering of Fig. 3 save that just sufficient to secure together

the multiple sheets prior to the dieing out of the completed puffs from the compound sheet), to conduct the rim-sewing of the disks as by hand after the dieing operation, as above described in connection with Fig. 4, as by overlock 24 of Fig. 4.

In order to keep down the labor-time charge in changing the sheet-relations between Figs. 2 and 3 (or between Figs. 2 and 1), it is desirable to perform the operations of Fig. 2 on as many horizontal rows as may be practicable; and we contemplate that with further experience we may be able to complete the operations of Fig. 2 for six or more horizontal rows, without impairing the necessary registration, instead of the four rows shown and above described. The advantage of using the large sheets in the mill width, as about one yard, is two-fold, i. e. (1) it involves less labor charge than that required to set up initially a plurality of narrower sheets, and (2) it avoids the more or less serious raveling which would result from cutting up a wide sheet into narrower sheets, and also, of course, it avoids the cost of such preliminary cutting-up. Furthermore, the embroidering upon the outer portions of the material of the puff disks prevents harmful raveling after dieing out, and this efficiency in preventing raveling goes to the root of the feature of not separating the puff disks from their large sheets by cutting thru such sheets to cut out the disks therefrom until after such ravel-preventing embroidering is effected. This feature is effective whether embroidery 2 be produced (circle 4 being produced in Fig. 3) or whether the same be replaced by overlock 24 of Fig. 4 (circle 3 being produced in Fig. 3).

The attention of makers of the invention is directed to the improvements and practical value of suspending the large sheets T, I and B vertically, hanging by gravity, in some such manner as by their edges, as shown in Figs. 1, 2 and 3; for this exposes the entire area of such large sheets freely to access for the multiple needleworking operations, whether manual or machine, as distinguished from the localization of the area of a single disk, (as in an ordinary individual sewing machine), to the vicinity of the needle and shuttle thereof, in which case there would be no advantage in employing large sheets on account of the impracticability of working substantially simultaneously on puffs distributed over a large area of the sheet. (Heretofore it has not been practicable to produce any such article as our new powder puff, because there was no known way of making it economically, and it could have been made, if at all, only by producing the embroidery individually on previously cut-out puffs, and these puffs are impracticably small for an ordinary embroidery frame, just as the large sheets of our invention are

impracticably large for an ordinary embroidery frame. Also the cut edges would have raveled or frayed during such attempted operations.) And, specifically, the suspension of the large sheets vertically, as shown in Figs. 1-3, adapts them, not only to substantially simultaneous working over large areas, in positions properly maintained by gravity, but to setting them up in connection with the plurality of needles in a horizontal row as in existing embroidering machines, so that it is not necessary, in order to employ the invention, to design a special embroidering or multiple stitching machine for adaptation to the invention. However, for the purpose of increasing economical production by the invention, the sets of rollers R and supporting curtains V of Figs. 1-3 may be duplicated or even triplicated, one above the other in the same vertical plane, in a machine which correspondingly may have two or three carriers C, Fig. 1, each supporting a horizontal row of needles N and corresponding shuttles, so that two or even three sets of large sheets T, I and B, as in Figs. 1-3, may be operated simultaneously in accordance with the invention under the control of the operator of the machine. In any embroidering machine with which the invention may be operated, the control may either be by pantograph, as mentioned above, or by perforated paper-roll control, as well known.

We are aware of the long prior proposal, in the U. S. patent to Neuberger No. 885,778 of 1908, to make ordinary rectangular sachet cushions or bags stuffed with perfumed material, by placing the perfumed stuffing between two sheets; then, in an ordinary hemstitching sewing machine, hemstitching the two sheets in lines at right-angles to one another, so as to include parts of the perfumed stuffing in a plurality of bags or pads separated from one another by the intervening hemstitching; and then severing the middle of the hemstitching along lines which result in segregating the bags from one another. This proposal, however, differs fundamentally from the present invention in the various respects pointed out above and in the claims.

The general configuration of the powder puffs hereof has been standardized substantially universally to circular toilet disks adapted to the circular compact boxes or to the toilet table powder boxes to which the general utility puff of Fig. 15 is adapted; and altho all such types are termed "puffs" in the trade, the type of puff of Figs. 4-4A is not very puffy, and even the type of Fig. 15 is different from the fluffy puff long used with powder in a box on the dressing table. Hence the claims herein more aptly define the product of any of the drawings as a "toilet disk". In the claims, also, the disk-sheets constituting the toilet disk are defined as follows. The ornamental top disk T, of

satin, silk or the like, or Figs. 4-4A, and the top disk T of Fig. 15, is defined as the ornamental top or simply as the top; the soft bottom disk-sheet B of Figs. 5 4-4A and Fig. 15 is defined as the soft bottom or simply bottom, this bearing the powder applying surface; and the intermediate stiffening disk-sheet I of Fig 1A and the intermediate disk I of Fig. 13 is defined as 10 the intermediate or filling disk. In the claims the word "plurality" means two or more; and the word "multiplicity" means substantially more than two or three. Ribbon or ribbon handle includes tabs. The word "embroidery" includes stitching or needlework within the proper scope of the invention. The word "disks" includes puff-sheets of any desired superficial configuration and is not limited to circular sheets.

15 Other variations of the manufacture will be suggested hereby to manufacturers, for example as follows. In Fig. 2 the reason for the operations on large ornamental sheet T not including soft bottom sheet B is in 20 order that embroiderings more or less central of the ornamental tops of the puff-disks may not extend, as to some of their threads at least, to the surfaces of soft bottom B, thereby not only producing an unattractive appearance, but constituting surfaces more or 25 less rough at the portions of soft bottom B which are rubbed over the facial skin of the puff-user. But when three sheets, T, I and B, are employed, as usually, the same object 30 can be attained by conducting the operations of Fig. 2 upon two adjacent sheets T and I but not B, the latter being kept in the position shown in Fig. 2 during such operations, but then changed, for the 35 operations of Fig. 3, to the position shown in the latter figure. But in the case of the general utility puff of Figs. 5-15 ornamental embroiderings inside securing circle 4 such as 1, cannot be made to extend thru two 40 sheets, on account of the operation of turning inside out, Figs. 13-14. And if only two large sheets in all are employed in Figs. 1-3, then the operations of Figs. 2 and 3 will be 45 conducted as therein shown, but with the second sheet in the position shown in Fig. 2 as occupied by the second and third sheets I 50 and B.

We particularly point out and distinctly claim the part, improvement or combination which we claim as our invention or discovery, as follows:

1. The improvement in the art of making toilet disks having a plurality of sheet-disks and a ribbon handle, which consists in supporting at least one relatively long sheet substantially taut in a vertical plane, with the length of the sheet extending horizontally; producing on said long disk-sheet, while so supported, for a multiplicity of toilet disks, 60 a multiplicity of like ornamental embroidery

designs spaced at intervals in a horizontal row along the length of the sheet; temporarily securing a ribbon horizontally along the length of said long sheet in a position adjacent said horizontal row of embroidered designs and within the vertical limits of the desired toilet disks; producing on said long sheet, and in said row, a second multiplicity of like embroidery stitchings in positions securing said ribbon to said long sheet; supporting at least another similarly long sheet in a vertical plane alongside the first sheet; and producing on the facing long sheets a third multiplicity of like embroidery stitchings, at corresponding intervals along the same horizontal row as the first and second stitchings in the first long sheet but extending entirely thru the facing long sheets, thereby securing the long sheets together at each of the plurality of trebly embroidered portions of the long resulting compound sheet, whereby the disk portions as permanently assembled disk-units, can be cut out of said long compound sheet.

2. The improvement in the art of making toilet disks having a plurality of sheet-disks and a ribbon handle, which consists in supporting at least one relatively long sheet substantially taut in a vertical plane, with the length of the sheet extending horizontally; temporarily securing a ribbon horizontally along the length of said long sheet; producing on said long sheet while so supported, for a multiplicity of toilet disks, a multiplicity of like embroidery stitching in a horizontal row along the length of the sheet and in positions securing said ribbon to said sheet and at intervals in the row corresponding with desired toilet disks; supporting at least another similarly long sheet in a vertical plane alongside the first long sheet; and producing on the facing long sheets a multiplicity of like embroidery stitchings at corresponding intervals in the same horizontal row as said designs stitched on the first long sheet but extending entirely thru the facing long sheets, thereby securing them together at each of the plurality of doubly embroidered disk-portions of the long resulting compound sheet, whereby the disk-portions, as permanently assembled disk-units, can be cut out of said long compound sheet.

3. The improvement in the art of making articles comprising a plurality of fabric sheets, consisting in supporting at least one relatively long and wide fabric sheet substantially taut with its width extending vertically and with its opposite surfaces exposed; producing on said sheet while so supported a multiplicity of ornamental embroidery stitchings at spaced intervals like one another in a horizontal row; supporting at least another similarly long and wide fabric sheet, in position in a plane alongside the first large sheet; producing on said facing

sheets a multiplicity of embroidery stitchings similarly spaced along the same horizontal row as said ornamental embroidery stitchings in the first sheet but extending entirely thru the facing sheets, and securing them together; removing from the surface of the first large sheet the portions of the second sheet not yet secured to the first sheet, leaving the faces of the first sheet free as before; repeating the production on the first large sheet of a horizontal row of a multiplicity of ornamental embroidery stitchings like one another but on a new portion of the area of said first large sheet; replacing alongside the first large sheet a portion of the second large sheet not yet secured thereto; and repeating the production, on the facing sheets, of a horizontal row of a multiplicity of embroidery stitchings like one another extending thru the facing sheets but on the same new portion of the area of the first sheet which contains the second row of ornamental embroidery stitchings.

4. The improvement in the art of making articles comprising a plurality of fabric sheets, which consists in supporting at least one relatively long and wide fabric sheet substantially taut in a vertical plane, with the opposite surfaces exposed; producing on said large sheet while so supported a multiplicity of ornamental embroidered designs like one another in a plurality of rows extending partially over the vertical extent of the sheet, the supported sheet being moved vertically between the embroiderings on the successive rows; supporting at least another similarly large fabric sheet alongside the first sheet; producing on said facing large sheets, successively on the same rows as on the first sheet, a multiplicity of embroidered stitchings, like one another, such stitchings respectively extending around the embroidery designs on the first sheet and also extending thru the plural sheets, including the bottom disk-sheet, securing them together; and the supported large plural sheets being moved vertically in the intervals of time between the embroiderings on the successive rows; removing the said second large sheet away from the surface of the first large sheet, leaving the surface of the latter exposed as before; moving the first large supported sheet vertically; repeating on the first sheet, but on a new portion thereof, the first above-specified production of a plurality of horizontal rows of ornamental embroiderings; replacing the second sheet adjacent the first; and repeating on the combined sheets, but on the second set of a plurality of horizontal embroidered rows on the first sheet, the first above-specified plurality of horizontal rows of embroidery stitchings on the combined sheets.

5. The improvement in the art of making toilet disks comprising a plurality of disk-

sheets and a ribbon-handle, which consists in temporarily attaching the ribbon-handle material along the length of a sheet which is long as compared with the disks; producing a plurality of embroidery designs extending thru said sheet at spaced intervals thereof and extending also thru said ribbon to secure the sheet and ribbon together permanently; and individually removing the toilet disks comprising portions of said sheet and ribbon-handle material secured by embroidery thereto, by independently making a plurality of cuttings thru the long sheet along circular lines surrounding the ribbon-securing embroiderings.

6. The improvement in the art of making toilet disks comprising a plurality of disk-sheets and a ribbon-handle, which consists in producing a plurality of ornamental embroidery designs spaced from one another on a comparatively large sheet; temporarily attaching the ribbon-handle material along the length of the sheet which is long as compared with the disks; collectively securing together the embroidered disk-sheets and ribbon-handles for a plurality of disks, by simultaneously producing a plurality of substantially circular embroiderings extending thru said sheet and also thru said ribbon-handle material, said circles being made to surround said embroidery designs but being more or less unevenly spaced from one another and serving to secure the disk-sheets and ribbon-material together; and individually separating the disk-sheets and ribbon-handles so assembled and secured together by embroidery, by independently making a plurality of cuttings thru the large sheet along circular lines concentric with the circular securing embroiderings but of larger diameter and surrounding the latter to permit severing the large sheets without cutting the stitches of the circular embroidery.

This specification signed this 30th day of September, 1925.
